[57] CLAIM

The ornamental design for a cheesecake in a cone, as shown and described.

DESCRIPTION

FIG. 1 is a front perspective view of a cheesecake in a cone, showing my new design, where the cheesecake is shown with the consistency of a cheesecake as opposed to the consistency of ice cream, frozen yogurt, or other frozen dessert;

FIG. 2 is a top view thereof;

FIG. 3 is a front elevational view thereof, the rear, left side, and right side elevational views being substantially identical thereto; and,

FIG. 4 is a bottom view thereof.
